THE COLUMBIA PLANOGRAPH CO., WASHINGTON, D. C.

UNITED STATES PATENT OFFICE.

ALBERT L. JOHNSON, OF LULING, TEXAS.

OIL-CONTROLLER.

1,173,976.

Specification of Letters Patent. Patented Feb. 29, 1916.

Application filed July 13, 1914. Serial No. 850,749.

To all whom it may concern:

Be it known that I, ALBERT L. JOHNSON, a citizen of the United States, residing at Luling, in the county of Caldwell, State of Texas, have invented certain new and useful Improvements in Oil-Controllers; and I do hereby declare the following to be a full, clear, and exact description of the invention, such as will enable others skilled in the art 10 to which it appertains to make and use the same.

This invention relates to burners such as are used in connection with steam boilers or the like.

15 More especially the invention relates to means of automatically controlling the flow of fuel and air or steam to the boiler burner.

The principal object of the invention is to improve and simplify the general construction of devices of this character.

20 A second object of the invention is to provide an improved device which will automatically control, at the same time, both the fuel and the air or steam supply valves so 25 that as the boiler pressure rises or falls the valves will be closed or opened in accordance with the variation of boiler pressure.

With the above and other objects in view 30 the invention consists in general of certain novel details of construction and combinations of parts hereinafter fully described, illustrated in the accompanying drawings, and specifically claimed.

In the accompanying drawings, like characters of reference indicate like parts in the 35 several views, and Figure 1, is a plan view of the device applied to a boiler. Fig. 2, is a front elevation of the device. Fig. 3, is a section on the line 3—3 of Fig. 1. Fig. 4 is a 40 section on the line 4—4 of Fig. 2. Fig. 5, is a detailed view of a cross bar used herewith. Fig. 6, is an enlarged detailed section showing the manner of adjusting the spring used herewith for different degrees of tension.

45 In carrying out the objects of this invention there is provided a cylinder pin which has an upper end closed by a plate 11 centrally provided with a threaded opening 12 whereto is secured a pipe 13 which leads to 50 the steam space of a boiler 14. Within this cylinder 10 is a piston 15 fitted with the usual follower plate 16 and cup 17. At the lower end of the cylinder 10 is a diaphragm 18 and the piston rod 19 extends through 55 this diaphragm and is secured in the usual manner to the piston 15. Above this dia-

phragm 18 is a plate 20 which is adjusted with respect to the diaphragm by means of the screws 21 and on this plate rests one end of a coil spring 22, the other end of this 60 spring bearing on the piston 15. By means of these screws 21 the tension of the springs may be adjusted as can be readily seen.

Extending downward from the lower end of the cylinders 10 are yoke members 23 and 65 these members are preferably formed integral with the cylinder 10 and have at their lower ends a fitting 24 formed with a guide pocket 25 in its upper surface, the piston rod having its lower end located in said guide 70 pocket. The fitting 24 is provided with a T-shaped passage 26 and to the branches of this passage are fitted respectively the fuel pipe 27 and the steam or air pipe 28, it being understood that either liquid or gaseous 75 fuel may be used. Each of these pipes 27 and 28 is provided with a valve casing 29 having a seat 30 therein and on these seats 30 are adapted to fit the valves 31. Each of these valves 31 has an upwardly extending 80 stem 32 which has its upper end threaded as at 33. The piston rod 19 is also threaded as at 85 34. Extending across the device is a bar 35 which has circular openings adjacent its ends and in its center for the reception of the stems 32 and the piston rod 19. This bar is held in position on the rod 19 by means of the nuts 36 and similarly the bar is held by nuts 37. Extending from the stem of the T-shaped passage 26 is a connection 90 38 to the burner in the fire box of the boiler.

In using the device the tension of the spring 22 is properly adjusted and also the valves 31 are adjusted by means of the nuts 37. Now when the boiler pressure rises 95 the piston 15 will be forced downward and thus carrying with it the valves 31 so that the valves will partially or wholly close the openings in the valve seats thus the supply of fuel and air or steam is reduced as the 100 boiler pressure rises and consequently the heat in the fire box is reduced which results in a decrease of the boiler pressure and the restoration of the piston to its position. In like manner if the boiler pressure falls the 105 spring 22 will force the piston upward and open the valves to a greater degree so that an increased flow of fuel and air are seen takes place with the result of increasing the 110 heat in the fire box and thus raising the boiler pressure to its proper point. There has thus been provided a simple and efficient

device of the kind described and of the character specified.

It will be obvious that many minor changes may be made in the form and construction of this invention without departing from the material principles thereof. It is not therefore desired to confine the invention to the exact form herein shown and described but it is wished to include all such as 10 come properly within the scope claimed.

Having thus described the invention, what is claimed as new is:

In a regulator of the class described, a cylinder, a yoke depending from the cylinder and having longitudinal slots formed in its arms, a bar slidably mounted in the slots, 15 a fitting carried by the lower ends of the yoke arms, a guide pocket formed centrally

in the fitting, means for connecting the cylinder to a boiler, a piston movable in the cylinder, a rod for the piston having its lower end slidably engaged in the pocket, a plurality of valves for controlling flow of fluid from the fitting to a burner, stems for the valves, said stems and piston rod being 20 adjustably connected to the bar and movable therewith, and a spring for the piston, and means for regulating the tension of the spring.

In testimony whereof I affix my signature, 25
in the presence of two witnesses.

ALBERT L. JOHNSON.
